THOMAS J. DALTON, OF HOUSTON, TEXAS.

COMBINATION PAPER-HOLDER AND DISPLAY DEVICE.

1,117,983.

Specification of Letters Patent. Patented Nov. 24, 1914.

Application filed September 11, 1913. Serial No. 789,254.

To all whom it may concern:

Be it known that I, THOMAS J. DALTON, a citizen of the United States, residing at Houston, in the county of Harris and State of Texas, have invented certain new and useful Improvements in a Combination Paper-Holder and Display Device, of which the following is a specification.

This invention relates to new and useful improvements in a combination paper holder and display device.

The object of the invention is to provide a device of the character described adapted to hold paper towels and paper for other toilet uses and embodies also a display mechanism whereby signs, or data of any character, may be displayed, said mechanism being operated as the paper is unwound from the roll.

With the above and other objects in view, the invention has particular relation to certain novel features of construction and operation, an example of which is given in this specification and illustrated in the accompanying drawings, wherein,

Figure 1 is a sectional side elevation of the device. Fig. 2 is an isometric view thereof, and Fig. 3 is a detail view of one of the bearings employed.

Referring now to the drawings, the numeral 1 refers to the casing which is a box-like structure whose lower portion 1^a extends out in front farther than the upper portion 1^b. Secured to each end of the box, on the inside, is an approximately triangular support, or brace, as 2 whose forward sides are inclined, as shown, and the inclined side of each brace has a semi-circular bearing as 3, in which the shaft 4, on which the spool 5 is mounted rests and in which it rotates. This spool is provided to receive the roll of towels or paper. A bar, as 6 is arranged at each end of the box 1, and hinged thereto at its lower end. These bars normally lie upon the inclined sides of the braces 2 and have semi-circular recesses, such as 7, which receive the ends of the shaft 4 and hold them in place.

A lid, or covering 8 is provided, which is hinged to the lower part of the front side thereof and which is provided with a latch 9 by means of which it may be fastened in closed position and when fastened in said position protects the paper and operates also to hold the bars 6 in position. When it is desired to remove the spool 5 and place a

new roll of paper in the device, the covering 8 may be unlatched and opened, the bars 6 withdrawn and the spool 5 removed from the shaft 4 and another spool bearing a complete roll of paper replaced thereon.

One end of the shaft 4 has a gear wheel 10 rigidly mounted thereon which meshes with a small gear wheel 11 fixed to the end of the transverse roller 12. This roller 12 is 65 rotatably mounted in the rear portion of the box and alined above it in the upper part of the portion 1^b is a similar transverse rotatable roller 13. These rollers have short shafts, as 14 and 15, respectively, projecting from the ends thereof. The shafts 14 are rotatable in suitable fixed bearings and the shafts 15 are rotatable in suitable sliding bearings, as 16 which slide in the members 17 depending from the top of the box 75 on each side. Each bearing 16 is slidably mounted on a rod 18 which is threaded through the top of the box and the lower end of each rod has an enlarged head 18^a interposed between which and the bearings 80 16 are coil springs 18^b forming a resilient cushion for the bearings 16. The tension on the springs 18^b is regulated by screwing the rods 18 up or down and the slack of the endless apron 19 thus regulated. This apron 85 passes over the rollers 12 and 13 and in front of the window 20 in the front of the portion 1^b of the box and said apron is designed to carry signs and advertising matter which will be displayed through the window 20. It is 90 obvious that as the tension on the springs 18^b is increased the roller 12 will be more difficult to turn and as said roller is operatively connected with the spool 5 the roll of paper may thus be prevented from unwinding 95 too freely.

Each end of the box has on the inside, pulleys 21, 22 and 23 upon which elastic cords or tapes as 24 operate. The pulleys are so positioned that the cords 24 will press against the paper roll and also prevent it from unwinding too freely. This expedient for preventing the free unwinding of the paper is not essential but may be used if desired. The free end of the paper, 105 forming the roll, projects out through a slot 25 in the front side of the box so that it may be grasped and the paper unwound. One end of the shaft 4 has a crank 26 so that in case the tensile strength of the paper is not 110 sufficient to unwind the paper from the roll, this crank can be used for that purpose.

It is obvious that as the paper is drawn out and the roll unwinds the gear wheel 10 will turn and in turn the gear wheel 11 and roller 12 will be rotated. This will operate 5 the apron 19 and the signs, or other matter printed thereon will be successively brought before the window 20.

What I claim is:—

1. A device of the character described including a casing, a rotatable spool mounted therein and provided to receive a roll of fabric, a covering for the casing, hinged thereto and having a transverse slot through which the free end of the fabric projects, said fabric being arranged so that a pull on the free end thereof will rotate the spool, a plurality of pulleys arranged in the casing and a cord operating over said pulleys and pressing against the roll of fabric 20 wound on said spool.

2. A device of the character described including a casing, bearing members at each end thereof, each having a semi-circular recess in its upper side, a rotatable spool provided to receive a roll of fabric, a supporting shaft carrying said spool and whose ends rest in said respective recesses, a bar arranged at each end of the casing and hinged thereto at its lower end, each bar 25 having a semi-circular recess in its underside, a covering for the casing, hinged thereto and having a transverse slot through which the free end of the fabric projects,

said covering, when closed, resting against said bars and holding them in position upon 35 said bearing member, said fabric being arranged so that a pull on the free end thereof will rotate the spool.

3. A device of the character described including a casing, bearing members at each 40 end thereof, each having a semi-circular recess in its upper side, a rotatable spool provided to receive a roll of fabric, a supporting shaft carrying said spool and whose ends rest in said respective recesses, a bar 45 arranged at each end of the casing and hinged thereto at its lower end, each bar having a semi-circular recess in its underside, a covering for the casing, hinged thereto and having a transverse slot through 50 which the free end of the fabric projects, said covering, when closed resting against said bars and holding them in position upon said bearing member, said fabric being arranged so that a pull on the free end thereof 55 will rotate the spool and means in contact with said spool and operating in resistance to the rotation thereof.

In testimony whereof I have signed my name to this specification in the presence of 60 two subscribing witnesses.

THOMAS J. DALTON.
